[57] CLAIM

The ornamental design for an article of flatware, as
 shown and described.

DESCRIPTION

FIG. 1 is a front elevational view of an article of flatware showing my new design as embodied in a fork;
 FIG. 2 is a side elevational view from the right of FIG.
 1;

FIG. 3 is a rear elevational view of FIG. 1;
 FIG. 4 is a cross-sectional view taken on line 4—4 of
 FIG. 1;

FIG. 5 is a cross-sectional view taken on line 5—5 of
 FIG. 1;

FIG. 6 is a front elevational view of an article of flatware showing my new design as embodied in a spoon,
 the rear view of the handle portion being similar to
 FIG. 5; and

FIG. 7 is a side elevational view from the bottom of
 FIG. 6.

The sides opposite the handle portions shown in FIGS.
 2 and 7 are mirror images of the respective sides shown.
 The distinguishing feature of my new design for an
 article of flatware resides in the handle configuration.
